(57) **CLAIM**

The ornamental design for a lid for kitchen utensil as shown and described.

DESCRIPTION

1. Lid for kitchen utensil

1.1 : Bottom

1.2 : Perspective

1.3 : Perspective

This design is related to a lid for pans and pots. The lid is round and curved and there is a hole in the center of the top. There are parallel wave-shaped reliefs on the inner surface from the hole to the edges of the lid.

1 Claim, 3 Drawing Sheets
